UNITED STATES PATENT OFFICE.

SAMUEL A. BENNER, OF PITTSBURGH, PENNSYLVANIA.

TRUCK-BOLSTER CONSTRUCTION.

1,215,766.

Specification of Letters Patent.

Patented Feb. 13, 1917.

Application filed March 27, 1914. Serial No. 827,523.

To all whom it may concern:

Be it known that I, SAMUEL A. BENNER, a citizen of the United States, and resident of Pittsburgh, in the county of Allegheny and State of Pennsylvania, have invented a new and useful Improvement in Truck-Bolster Construction; and I do hereby declare the following to be a full, clear, and exact description thereof.

16 My invention relates to improvements in car bolsters and is particularly concerned with construction of a bolster which may be made entirely of rolled or pressed sections of metal. The primary object is to construct 20 the compression and tension members each of wrought integral sections.

A further object is to construct a bolster of this character which will possess the greatest possible strength for the amount 25 of metal used. This is primarily accomplished by producing the compression and tension members from special sections rolled on a structural guide mill instead of a plate mill, thus obtaining thickness or thinness of material where desired.

30 A further object is to so construct, arrange and secure the parts of the bolster together, that the compression and tension members will be united or riveted together along or 35 near the lines of neutral strain of the bolster. That is to say, along lines intermediate of the lines of greatest compression strain on the one hand, and of greatest tension strain on the other. These lines, of course, may be 40 readily determined by those skilled in the art of metal constructions.

A further object is to so construct the bolster that the attachment of the center and side bearing plates will serve to secure the 45 parts of the compression member against a tendency either to spread or to collapse.

46 A further object is to provide means for securing the side walls of the bolster along lines intermediate of the depth thereof 50 against spreading and in this connection means are provided which serve not only as spread preventing means, but also as a pocket or socket for the king pin within the bolster body.

55 A further object is to so construct the sections which form the tension and compression members of the bolster, that they will present the greatest possible strength along the lines of greatest compressional and tensional strain.

A further object is to so reinforce the sides of the bolster as to insure rigidity against lateral bending and twisting strains on the bolster.

60 A further object is to so construct and arrange the parts of the bolster as to facilitate the riveting together of said parts and particularly to provide for open outside riveting for the center and side bearings.

65 While a specific application of the structure broadly covered by this invention may be in the form of a car bolster, it is obvious that the same structure including the compression and tension members may be employed as a car sill, particularly a center 70 sill. One of the objects of this invention, therefore, is to provide such structure.

75 With these objects in view, the invention consists in the constructions and arrangements of parts, preferred embodiments of which are illustrated in the accompanying drawings, in which Figure 1 is a side elevation of a bolster adapted for use on a forty to fifty ton car. Fig. 2 is a plan view of 80 the bolster shown in Fig. 1. Fig. 3 is a sectional view on the line 3—3, Fig. 1; Fig. 4 is a sectional view on the line 4—4, Fig. 1; Fig. 5 is a view corresponding to Fig. 4, showing a modified form of the construction; 85 Fig. 6 is a view corresponding to Fig. 4, showing a further modification, and Fig. 7 is a sectional view corresponding to the section 3—3, Fig. 1, illustrating modifications of the forms of the rolled sections 90 employed as the compression and tension members of a bolster before said sections have had their reinforcing flanges cut or sheared to finished form. Fig. 8 is a central vertical section of the rolled sections 95 shown in Fig. 7. Fig. 9 is a view corresponding to Fig. 7, showing a further modification of the bolster sections. Fig. 10 is a sectional view corresponding to the section Fig. 8 of the members shown in Fig. 100 9. Fig. 11 is a plan view of a blank for the compression member of a bolster with wide ends and narrow center intended for a sixty to seventy ton car, showing the manner in which the lateral reinforcing flanges and 105 the central web are sheared or cut away prior to bending the section to bolster shape. Fig. 12 is a plan view of a bolster in which a section similar to that shown in Fig. 11 is employed as the compression member. 110

Fig. 13 is a side elevation of the bolster shown in Fig. 12. Fig. 14 is a central sectional view on the line 15—15, Fig. 12. Fig. 15 is an end sectional view on the line 16—16, Fig. 12. Fig. 16 is a perspective and partial sectional view of a central reinforcing and king pin socket forming member for the compression member of the bolster. Fig. 17 is a perspective view of a modified form of king pin socket. Fig. 18 is a side elevation of a modification of the bolsters of the forms shown in Figs. 1 to 13, respectively; Fig. 19 is a view showing two bolster members used together as body and truck bolsters, respectively. Fig. 20 is a longitudinal section of the bolster shown in Fig. 13. Fig. 21 is a perspective view of the rolled or wrought section from which the fish-belly compression member is formed. Fig. 22 illustrates the steps by which the blank shown in Fig. 21 is pressed into fish-belly shape. Fig. 23 is a view of a modified form of blank for a king-pin socket and Fig. 24 is a perspective view in section showing the completed form of said socket.

In the modification of the invention illustrated in Figs. 1 to 4 inclusive, the bolster consists primarily of two rolled sections, namely, the upper section 1 forming the compression member and the lower section 2, the tension member. In the compression member in the form illustrated in these figures, the rolled section comprises (Fig. 3), a web 3 and the side-walls 4—4. At the junction of the web and side walls are lateral flanges 5—5. These flanges, as illustrated in Fig. 2, are sheared away at 6—6 near the ends of the bolster, thus leaving lateral reinforcing members extending throughout the main portion of the bolster to withstand lateral bending or twisting strains. The shearing off of the ends of these flanges reduces the extremities of the bolster to substantially the proper width to be received within the pedestal opening of the truck side-frames. The lower edges of the side-walls 4—4 of these compression sections are provided with inturned flanges 7—7 and with outwardly extending flanges 8—8, the extremities of the latter being also sheared in the manner indicated at 6—6, Fig. 2, for the flanges 5—5. The flanges 7—7 may also be sheared at 7'—7', as the flanges 5—5 and 8—8 furnish sufficient lateral strength at the midportion of the bolster. The tension member of the bolster consists primarily of a rolled section which as originally rolled is of the channel shape shown in Fig. 21, and provided with lateral wings or flanges, and with a longitudinal thickened strengthening portion 9. This channel section is then placed in a press and the ends thereof are forced up or flattened as shown in Fig. 22, and the surplus metal at 10—10' is sheared off on the lines 10—10', Fig. 22, leaving the central fish-bellied shape shown in side elevation in Fig. 1, the end elevation in Fig. 3, the transverse sectional view shown in Fig. 4, and as in perspective in Fig. 22. Thus the tension member comprises at opposite extremities, the flat portions which in cross section have the shape shown in sectional view in Fig. 3, including the thickened portion 9, which is received between the inturned flanges 7—7 of the compression member and the thinner lateral edges of which extend beneath said flanges 7—7, and as at 10—10, beneath the out-turned flanges 8—8 of the compression member. The outer edges of the wings or flanges of the tension member are cut away at the opposite extremities in the same manner as the flanges 5—5, and 8—8, of the compression member at 6, Fig. 2, thus making the ends of the bolster of uniform width throughout the depth thereof. The outer edges or flanges 10—10 of the tension member are riveted to the flanges 8—8 of the compression member as at 11 and the thinner portions of the web of the tension member are riveted at the opposite ends of the bolster to the in-turned flanges 7—7 of the compression member as shown at 12, Fig. 3. Thus it will be seen that the lines of rivets which unite the compression and tension members, correspond to 95 or extend substantially along the neutral lines of compression and tension strains on the bolster. Consequently, there is little tendency to shear the rivets at the joints of the compression and tension members, which are subjected to the least amount of relative movement of said members. This is of peculiar advantage in a bolster construction where the strains are particularly severe.

The thickened portion 9 of the web of the tension member presents a particularly strong construction at the ends of the bolster for receiving the pressure of the bolster springs, and this strength is enhanced by the presence of the flanges 7 to which the web of the tension member is secured. This thickened portion 9 moreover, since it extends along the bottom of the fish-belly portion of the tension member, reinforces the same along the lines of greatest tensile strain.

The ends of the bolster are provided with pedestal guide plates 13, having the vertical ribs 14 which engage the side-walls of the pedestal opening. These plates may be readily riveted through the side-walls of the bolster. The bolster is also provided with the usual center bearing plate 15 which as shown in Figs. 3 and 4, is riveted to the flanges 5 of the compression member, and this provides a transverse reinforcing member for the bolster. The side bearing plates 16 are similarly riveted to the flanges 5 and form further reinforcing members.

In the form of the invention illustrated in 136

Fig. 5, the center portion of the interior of the bolster may be provided with a transverse strengthening plate 17, riveted at 18 to the in-turned flanges 7 of the compression member, to prevent spread of the bolster body at the center.

In the form of the invention illustrated in Fig. 6, the compression member may consist of a rolled section similar to that heretofore described, but without the in-turned flanges 7. In this case the out-turned flanges 8 of the compression member and the out-turned flanges 10 of the tension member are not sheared away on the lines 6 as shown in Fig. 2, but extend out to the ends of the bolster. With this form of bolster, of course, a pedestal must be used having its bolster-receiving opening at the bottom, of sufficient width to receive the full width of the bolster ends, including these flanges. The narrower or bolster-bearing portion of the pedestal, however, need only be wide enough to receive the width of the bolster ends including the wearing plates 13, and the laterally extending flanges of the bolster body may be notched opposite the ends of these wearing plates.

In the form of the invention illustrated in Figs. 7, 8, 9 and 10, the compression member of the bolster is of the same form as that illustrated in Fig. 6, but showing modifications in the form of the web of the tension member. Thus, for example, in Figs. 7 and 8, the web is thickened at 19 throughout the width comprised between the side-walls 20 of the tension section. In Figs. 9 and 10, the web 21 is of the same thickness as the side-walls 22.

The construction heretofore described, and as shown in Figs. 1 to 6 inclusive, is intended primarily for use in bolsters for from forty to fifty ton cars. It is to be understood, of course, however, that these constructions may be so modified and strengthened as to adapt them for heavier cars.

In Figs. 11 to 16, inclusive, is illustrated a construction of bolster which is adapted primarily for use in heavier cars, say of capacity from sixty to seventy tons or over, with wider ends to provide greater bearing area for an increase in the number of springs on which the ends of the bolster rest.

In Fig. 11 is illustrated in plan view a rolled section corresponding in structure to the compression section shown in Fig. 3, but preferably of larger dimensions and of heavier material. This section comprises the web 30 having the upper side flanges 31-31, side-walls 32, lower in-turned flanges 33, and lower out-turned flanges 31'-31'. These upper outer flanges 31 and lower outer flanges 31'-31', are sheared off along the lines 34, back to the side-walls 32, thus reducing the ends of the bolster section to a width suitable to be received with-

in the bolster opening of the truck pedestal. The in-turned flanges 33 are also sheared away on lines 33'-33' as hereinbefore described. The web 30-30 is slotted or cut away as at 35 for the purpose of permitting the central portion of the compression member of the bolster to be compressed laterally or drawn together, as illustrated in Fig. 12. When so drawn together the side-walls of the compression member after compression, consist of end portions 32 standing at the original distance apart, intermediate compressed portions 36, which join the central compressed portions 37 of the side-walls with the uncomressed ends. The main purpose of so compressing the central portion of the compression member is to bring the outer edges of the flanges 31 within the width of a standard center bearing-plate such as 38, so that the edges of this plate may be riveted as at 39 through these flanges 31 as shown. Likewise, this compression brings the width within the dimension of the standard side bearing plates 40 which are likewise riveted at 41 to the flanges 31. This construction has the advantage that the securing in place of the center and side bearing plates serves to hold the sides of the compression member against spreading. Furthermore, inasmuch as the edges of the center plate and the ends of the side plates extend out over and are secured to outside flanges 31, the riveting together of these parts is all done on the outside and is thus facilitated. Also, broken plates may be easily replaced.

The tension member in this construction is of fish-belly shape, but is narrower in cross section than the ends of the compression member, in order to bring the side-walls 42 of said tension member directly under the contracted portion 37 of the side-walls 32 of the compression member throughout the central portion of the bolster, where the effect of the compression and tension strains is greatest. This tension section is provided with lateral flanges 43 which, intermediate the ends of the bolster, are riveted as at 44, to the exposed portions of the compression member flanges 31', whereas at the ends of the bolster, the flat end portions of the tension member are riveted as at 44', Figs. 13, and 15, to the inturned flanges 33 of the compression member. Thus, it is possible to rivet or secure the compression and tension members of the bolster together along lines at or near the lines of neutral compression and tension strains on the bolster. It is obvious that compression and tension strains such as exist at and to either side of the longitudinal center of the bolster, do not exist to the same degree or in the same relation to the bolster structure at the opposite ends since these ends are directly supported on the bolster springs. The ten-

sion member is provided with a thickened longitudinal portion 45, which extends throughout its length and at its ends is received between the edges of the inturned 5 compression section flanges 33. By this construction, as in the construction previously described, the tension member is strongest along the lines of greatest tension strain. The opposite ends of the bolster are provided 10 with pedestal guide and wearing plates 46, riveted directly to and through the side-walls 32 of the compression member as at 47. Thus is produced a bolster for heavy tonnage cars which is of the required width at 15 the ends to fit the greater width of the bolster receiving opening of heavy tonnage side frame pedestals and at the same time the bolster is preferably, in its general outline, of substantially uniform width throughout and so constructed as to possess an ample margin of safety at the center against all twisting and compression and tension strains.

20 In order that the weight on the bolster may be carried equally by the flat end portions 44 of the tension member and the web 30 of the compression member, reinforcing members or diaphragms, such as short I-beam sections 48, are secured within the ends of the bolster. The flanges of these I-beam sections may be riveted to the web 30 of the compression member and the flat end portions 44 of the tension member. 25 While I have described these reinforcing members as I-beam sections, it is obvious that they may be of other form, for example, simple channel sections, or box-like members.

30 In order to strengthen and bind together the central portions of the side-walls of the compression member, and at the same time to provide a socket or pocket for the reception of the lower end of the king bolt, I provide a structure of the character shown 35 in Fig. 16, which consists of a channel portion having the base 49; side-walls 50, lateral flanges 51, and depending securing wings 52, formed preferably as continuations of the 40 flanges 51. The channel portion of this member extends preferably transversely of the bolster and the depending wings 52 are riveted to the side-walls 32 of the compression member, as at 53. Within this channel member and before it is secured within the compression member of the bolster, I secure short vertical channel members each comprising a web 54, and the flanges 55. The latter are secured to the side-walls 50 of the 45 device as at 56, thus forming in effect with the channel member, a pocket or socket for the reception of the king pin. If desired, a cylindrical sleeve or bushing may be secured in this pocket or socket to snugly 50 surround and firmly hold the king pin.

55 against wobbling. As an alternative construction of the king pin socket, to that just described, the same may be constructed as shown in Fig. 17, and may comprise a channel member consisting of the web 57, 70 side-walls 58, horizontal wings 59 and depending wings 60, which device may be secured within the compression member, as shown in said figure, with the channel portion extending longitudinally instead of 75 transversely to said member. Short channel sections similar to those before described, and each consisting of a web 61 and side-flanges 62 may be secured within the channel portion of the device, to complete the king pin socket. It will be noted 80 that these king pin socket members serve to strengthen the bolster laterally and co-operate with the center plate to prevent spreading of the side-walls of the bolster. 85 It is obvious that the construction of the king pin socket member, as well as that of several other of the auxiliary parts or attachments of the bolster, may be varied, and may in some instances be made of castings 90 instead of rolled sections.

In Figs. 23 and 24 is illustrated a still further modification of the king pin socket. In this case this socket may be formed from a disk 63 by spinning down a socket portion '63' in the center in somewhat the same manner and on the same character of machine as is used for spinning wrought car wheels. The blank is then sheared along the lines 64 and the end portions 65 are then 95 bent down along lines 66 at right angles, as shown in Fig. 24, and the extremities of these end portions are sheared off straight as at 67. The socket member so formed is riveted to the side walls of the bolster 100 through the perforations 68. While I have described this socket member as formed from a circular disk, it is obvious that the same form of socket member may be spun 105 from a blank of square or oblong shape. 110

In Fig. 19 two similar bolster members 69 and 70 are illustrated of the fish-belly form and construction heretofore described, but equipped to be used together as a body bolster on the one hand and a truck bolster 115 on the other. In this case, the body bolster is provided with the side bearing members or plates 71 and a center plate 72, while the truck bolster is provided with the side bearing members 73 and center bearing plate 120 74. Also this truck bolster is provided with the pedestal guide plates 75. As shown in Fig. 20, the truck bolster and in fact both the body and truck bolster, may be provided at the ends with the transverse 125 strengthening beams or members 76.

In the form of the invention illustrated in Fig. 18 the bolster may consist of compression member and tension member having their flanges united by the rivets 77 130

substantially as before described, but this bolster may be further strengthened if desired by bending the compression and tension members upwardly as at 78 to form in effect a more or less arch-like construction. It is obvious that this arch construction may apply either to a bolster of the character shown in Figs. 1 to 4, or that shown in Figs. 12 to 15.

10 While I have shown and described particular constructions and arrangements of parts in the several embodiments of the invention here presented, and have shown and described the particular structures of the 15 several elements of the bolster, and have indicated special forms in which they may be advantageously manufactured, it is to be understood that the invention may be altered in any or all of the details set forth 20 within the scope of the appended claims.

What I claim is:

1. A car bolster comprising an integral rolled steel compression member consisting of a top web with outwardly opening channel members extending along either edge thereof, and an integral rolled steel tension member of fish belly shape having flattened ends secured to the ends of said channel members and having flanges intermediate its ends secured to the lower flanges of said channel member.

2. A car bolster comprising an integral rolled steel compression member consisting of a top horizontal web and side walls of channel form and an integral rolled steel tension member of fish belly shape having flattened ends secured to the lower flanges of said channel members and having lateral flanges intermediate of its ends also secured to the lower flanges of said channel members.

3. A car bolster comprising a compression member consisting of a single rolled section having a horizontal web and outwardly opening channel formed side walls, and a tension member consisting of a rolled section of fish belly shape, having flattened ends secured to the extremities of said channel members and having out-turned flanges intermediate of its ends riveted to the lower out-turned flanges of said channel members.

4. A car bolster comprising a compression member consisting of a single rolled section having a horizontal top web and outwardly opening channel form side walls having in-turned flanges at their lower edges and a tension member consisting of a rolled and pressed section of fish belly form having flattened ends secured to the lower flanges of said side walls and having lateral flanges intermediate its ends also secured to the lower flanges of said side walls.

5. A car bolster comprising a compression member consisting of a rolled section of channel form, the web of said section being

extended into lateral flanges extending outwardly throughout the length of said section, the outer edges of the side walls of said section having in-turned and out-turned flanges throughout the length thereof, and a 70 tension member consisting of a rolled channel section having a thickened portion extending longitudinally throughout the length of the web thereof, said section being pressed intermediate its ends to fish belly 75 shape leaving flat end portions and lateral out-turned flanges extending throughout the length of the section, said end portions and flanges being riveted to the flanges at the outer edges of the side walls of said compression member.

6. A car bolster comprising a compression member consisting of a rolled section of channel form, the web of said section being extended into lateral flanges extending outwardly throughout the length of said section, the outer edges of the side walls having in-turned and out-turned flanges throughout the length thereof, and a tension member consisting of a rolled channel section having a thickened portion 85 extending longitudinally throughout the length of the web thereof, said section being pressed intermediate its ends to fish belly shape, leaving flat end portions and lateral out-turned flanges 90 extending throughout the length of the section, said flat end portions being riveted to the in-turned flanges at the outer edges of the side walls of the compression member and said lateral flanges being riveted to the out-turned flanges of said side walls of the compression chamber.

7. A car bolster comprising a compression member consisting of a rolled section of channel form, the web of said section being 105 extended into lateral flanges extending outwardly throughout the length of said section, the outer edges of the side walls having in-turned and out-turned flanges throughout the length thereof, and a tension member 110 consisting of a rolled channel section having a thickened portion extending longitudinally throughout the length of the web thereof, said section being pressed intermediate its ends to fish belly shape, leaving flat 115 end portions and lateral out-turned flanges extending throughout the length of the section, said flat end portions being riveted to the in-turned flanges at the outer edges of the side walls of the compression member and said lateral flanges being riveted to the lower out-turned flanges of said side walls, said outside flanges of the compression member and the flattened ends of the tension member being sheared off flush with the side walls 120 of the compression member at the ends of the bolster.

8. A car bolster comprising a compression member, consisting of a rolled section of channel form, the web of said section being 130

- extended into lateral flanges extending outwardly throughout the length of said section, the outer edges of the side walls having inturned and out-turned flanges throughout the length thereof, and a tension member consisting of a rolled channel section having a thickened portion extending longitudinally throughout the length of the web thereof, said section being pressed intermediate its ends to fish belly shape, leaving flat end portions and lateral out-turned flanges extending throughout the length of the section, said flat end portions being riveted to the inturned flanges at the outer edges of the side walls of the compression member and said lateral flanges being riveted to the out-turned flanges of said side walls, said outside flanges of the compression member and the flattened ends of the tension member being sheared off flush with the side walls of the compression member at the ends of the bolster, and pedestal guide plates secured to the opposite sides of the ends respectively of the bolster.
9. A car bolster comprising a compression member consisting of an inverted channel shaped rolled section having flanges projecting laterally from the top plate or web thereof, a tension member consisting of a rolled section of fish belly shape secured to the lower edges of the walls of the compression member, a center bearing plate and side bearing plates riveted to said flanges of the compression member, whereby the bolster is strengthened against spreading of the side walls thereof.
10. A car bolster comprising an integral rolled steel compression member formed of an inverted channel shape having channel sides and a tension member consisting of a rolled section depressed intermediate its ends to fish belly shape and having lateral out-turned flanges adapted to be riveted to the out-turned flanges of the compression member, whereby the junction lines of said members will be at or near the neutral line of compression and tension strains.
11. A car bolster comprising an integral rolled steel compression member formed of an inverted channel shape having channel sides and a tension member consisting of a rolled section depressed intermediate its ends to fish belly shape and having lateral out-turned flanges adapted to be riveted to the out-turned flanges of the compression member, whereby the junction lines of said members will be at or near the neutral line of compression and tension strains, the flat ends of said tension member being trimmed to the width of the ends of the compression member and secured to the lower edges of the side walls of said compression member.
12. A car bolster comprising a compression member formed of an inverted rolled channel section, having flanges laterally ext-
- tending from the web thereof, and having flanges extending both outwardly and inwardly from the lower edges of the side walls of the compression member.
13. A car bolster comprising an inverted rolled channel section, having flanges laterally extending from the web thereof, and having flanges extending both outwardly and inwardly from the lower edges of the side walls thereof, and struts secured to and extending down the side walls of the bolster to prevent lateral spreading thereof.
14. A car bolster comprising an inverted channel shaped rolled section, and a tension member comprising a rolled section having its central portion depressed into fish belly form, a strengthening rib formed integrally with and extending longitudinally of the center of said tension member, the ends and side walls of said tension member being secured respectively to the ends and side walls of said compression member.
15. A car bolster comprising a compression member consisting of a top web with outwardly opening channel members extending along either side and a tension member of fish belly shape having flattened ends secured to the ends of said channel members and having flanges intermediate its ends secured to the lower flanges of said channel members, and a center bearing plate extending across the central portion of said bolster, and having its lateral edges secured to the edges thereof and a king pin socket and reinforcing member interposed between the side walls of said compression member beneath the center plate, and secured to said side walls.
16. A car bolster comprising a compression member consisting of a top web with outwardly opening channel members extending along either side, and a tension member of fish belly shape having flattened ends secured to the ends of said channel members and having flanges intermediate its ends secured to the lower flanges of said channel members; and a king pin socket and bolster reinforcing member formed of a channel shaped rolled section secured to the side walls of the compression member beneath the center plate, said king pin member having diaphragms secured within its channel forming a socket for the reception of the end of the king pin.
17. A bolster comprising a compression member, consisting of an inverted channel shaped rolled section having out-turned and inturned flanges at the lower edges of its side walls, the web of said section being slotted along its longitudinal center intermediate the ends, said out-turned flanges being sheared off adjacent the ends of said section, said section being laterally contracted intermediate its ends, whereby the side walls will be closer together in the middle of the bolster than at the ends of the bolster.

18. A bolster comprising a compression member consisting of an inverted channel shaped rolled section having the web laterally extended into out-turned flanges and having out-turned and in-turned flanges at the lower edges of its side-walls, the web of said section being slotted along its longitudinal center intermediate the ends, said out-turned flanges being sheared off adjacent the ends of said section, said section being laterally contracted intermediate its ends whereby the body portion thereof, including the unsheared portions of said flanges, will be brought to a width equal to substantially the width of the sheared ends and substantially equal to the width of a standard center plate, and a center plate and side bearing plates riveted to the unsheared portions of the out-turned flanges of the web of the intermediate portion of said section. 65
19. A bolster comprising a compression member consisting of an inverted channel shaped rolled section having the web laterally extended into out-turned flanges and having out-turned and in-turned flanges at the lower edges of its side walls, the web of said section being slotted along its longitudinal center intermediate the ends, said out-turned flanges being sheared off adjacent the ends of said section, said section being laterally contracted intermediate its ends whereby the body portion thereof, including the unsheared portions of said flanges, will be brought to a width equal to substantially the width of the sheared ends and substantially equal to the width of a standard center plate, and a center plate and side bearing plates riveted to the unsheared portions of the out-turned flanges of the web of the intermediate portion of said section. 80
20. A bolster comprising a compression member consisting of an inverted channel shaped rolled section having the web laterally extended into out-turned flanges and having out-turned and in-turned flanges at the lower edges of its side walls, the web of said section being slotted along its longitudinal center intermediate the ends, said out-turned flanges being sheared off adjacent the ends of said section, said section being laterally contracted intermediate its ends whereby the body portion thereof, including the unsheared portions of said flanges, will be brought to a width equal to substantially the width of the sheared ends and substantially equal to the width of a standard center plate, and a center plate and side bearing plates riveted to the unsheared portions of the out-turned flanges of the web of the intermediate portion of said section, and pedestal bearing plates secured to the side walls of said section, adjacent the ends thereof. 90
21. A bolster comprising a compression member, consisting of an inverted channel shaped rolled section having out-turned and in-turned flanges at the lower edges of its side walls, the web of said section being slotted along its longitudinal center intermediate the ends, said out-turned flanges being sheared off adjacent the ends of said section, said section being laterally contracted intermediate its ends, whereby the body portion thereof, including the unsheared portions of said flanges, will be brought to a width substantially equal to the width of the sheared ends and substantially equal to the width of a standard center plate, and a tension member formed of a flat rolled section depressed to fish belly shape intermediate its ends and having flat ends adapted to be secured to the in-turned flanges of the side walls of the compression member at the ends thereof, and having out-turned flanges adapted to be secured to the out-turned flanges at the lower edges of the central portions of said side walls. 95
22. A bolster comprising a compression member, consisting of an inverted channel shaped rolled section having out-turned and in-turned flanges at the lower edges of its side walls, the web of said section being slotted along its longitudinal center intermediate the ends, said out-turned flanges being sheared off adjacent the ends of said section, said section being laterally contracted intermediate its ends, whereby the side walls of the body portion thereof will be closer together in the middle of the bolster than at its ends, and reinforcing diaphragms secured to the web and to the lower in-turned flanges of said compression member, adjacent the ends of said section, to form reinforcement to receive the thrust of the bolster springs. 100
23. A bolster comprising a compression member, consisting of an inverted channel shaped rolled section having out-turned and in-turned flanges at the lower edges of its side walls, the web of said section being slotted along its longitudinal center intermediate the ends, said out-turned flanges being sheared off adjacent the ends of said section, said section being laterally contracted intermediate its ends, whereby the body portion thereof, including the unsheared portions of said flanges, will be brought to a width substantially equal to the width of the sheared ends and substantially equal to the width of a standard center plate, and a king pin socket and bolster reinforcing member secured within the section to the side walls thereof, below the center plate of the bolster. 110
24. A bolster comprising a compression 115

- 125

member, consisting of an inverted channel shaped rolled section having out-turned flanges at the lower edges of its side walls, the web of said section being slotted along its longitudinal center intermediate the ends, said out-turned flanges being sheared off adjacent the ends of said section, said section being laterally contracted intermediate its ends, whereby the side walls will be closer together in the middle of the bolster than at the ends of the bolster.

25. A bolster comprising a compression member consisting of an inverted channel shaped rolled section having the web laterally extended into out-turned flanges and having out-turned flanges at the lower edges of its side walls, the web of said section being slotted along its longitudinal center intermediate the ends, said out-turned flanges being sheared off adjacent the ends of said section, said section being laterally contracted intermediate its ends whereby the body portion thereof, including the unsheared portions of said flanges, will be brought to a width equal to substantially the width of the sheared ends and substantially equal to the width of a standard center plate, and a center plate and side bearing plates riveted to the unsheared portions of the out-turned flanges of the web of the intermediate portion of said section.

26. A bolster comprising a compression member consisting of an inverted channel shaped rolled section having the web laterally extended into out-turned flanges and having out-turned flanges at the lower edges of its side walls, the web of said section being slotted along its longitudinal center intermediate the ends, said out-turned flanges being sheared off adjacent the ends of said section, said section being laterally contracted intermediate its ends whereby the body portion thereof, including the unsheared portions of said flanges will be brought to a width equal to substantially the width of the sheared ends and substantially equal to the width of a standard center plate, and a center plate and side bearing plates riveted to the unsheared portions of the out-turned flanges of the web of the intermediate portion of said section; and pedestal wearing plates secured to the side walls of said section, adjacent the ends thereof.

27. A bolster comprising a compression member, consisting of an inverted channel shaped rolled section having its web laterally extended into out-turned flanges and having out-turned flanges at the lower edges of its side walls, the web of said section being slotted along its longitudinal center intermediate the ends, said out-turned flanges being sheared off adjacent the ends of said section, said section being laterally contracted intermediate its ends, whereby the body portion thereof, including the unsheared portions of said flanges, will be brought to a width substantially equal to the width of a standard center plate, and a center plate and side bearing plates riveted to the unsheared portions of the out-turned flanges of the web of the intermediate portion of said section; and pedestal wearing plates secured to the side walls of said section, adjacent the ends thereof.

28. A bolster comprising a compression member consisting of an inverted channel shaped rolled section having out-turned flanges at the lower edges of its side walls, the web of said section being slotted along its longitudinal center intermediate the ends, said out-turned flanges being sheared off adjacent the ends of said section, said section being laterally contracted intermediate its ends, whereby the body portion thereof, including the unsheared portions of said flanges, will be brought to a width substantially equal to the width of a standard center plate, and forming box-like ends of proper width to be received within the bolster opening of a truck side frame, and whereby a center bearing plate and side bearing plates of standard dimensions may be secured to the unsheared portions of the flanges of the web of said section.

29. A bolster comprising a compression member consisting of an inverted channel shaped rolled section having out-turned flanges at the lower edges of its side walls, the web of said section being slotted along its longitudinal center intermediate the ends, said out-turned flanges being sheared off adjacent the ends of said section, said section being laterally contracted intermediate its ends, whereby the body portion thereof, including the unsheared portions of said flanges, will be brought to a width substantially equal to the width of the sheared ends and substantially equal to the width of a standard center plate, and a tension member formed of a flat rolled section depressed to fish belly shape intermediate its ends and having flat ends adapted to be secured to the out-turned flanges of the side walls of the compression member at the ends thereof, and having out-turned flanges adapted to be secured to the out-turned flanges at the lower edges of the central portions of said side walls.

30. A bolster comprising a compression member, consisting of an inverted channel shaped rolled section having out-turned flanges at the lower edges of its side walls, the web of said section being slotted along its longitudinal center intermediate the ends, said out-turned flanges being sheared off adjacent the ends of said section, said section being laterally contracted intermediate its ends, whereby the side walls of the body portion thereof will be closer together in the middle of the bolster than at its ends, and reinforcing diaphragms secured to the web of said compression member adjacent the ends of said section to form reinforcements to receive the thrust of the bolster springs.

31. A bolster comprising a compression member, consisting of an inverted channel shaped rolled section having out-turned flanges at the lower edges of its side walls, the web of said section being slotted along its longitudinal center intermediate the ends, said out-turned flanges being sheared off adjacent the ends of said section, said section being laterally contracted intermediate its ends, whereby the body portion thereof, including the unsheared portions of said flanges, will be brought to a width substantially equal to the width of a standard center plate, and a center plate and side bearing plates riveted to the unsheared portions of the out-turned flanges of the web of the intermediate portion of said section; and pedestal wearing plates secured to the side walls of said section, adjacent the ends thereof.

tially equal to the width of the sheared ends and substantially equal to the width of a standard center plate, and a king pin socket and bolster reinforcing member secured within the section of the side walls thereof, below the center plate of the bolster.

31. A car bolster comprising a compression member formed of an inverted channel shaped rolled section having its central portion laterally contracted to the width of a standard center plate, and a tension member formed of a rolled section having its central portion depressed to fish belly shape, said tension member at its central portion being of a width corresponding to the contracted portion of the compression member and having flat ends flared to correspond in width to the wider end portions of the compression member, said tension member being secured to the lower edges of the side walls of said compression member.

32. A car bolster comprising an integral rolled steel compression member consisting of a top web with outwardly opening channel members extending along either edge thereof, and an integral rolled steel tension member of fish belly shape having flattened ends secured to the ends of said channel members and having flanges intermediate its ends secured to the lower flanges of said channel members, reinforcing diaphragms located within the ends of said bolster and secured to the top web of the compression member and to the flattened ends of the tension member.

33. A car bolster comprising a compression member consisting of a rolled section of channel form, the web of said section being extended into lateral flanges extending outwardly throughout the length of said section, the outer edges of the side walls of said section having inturned and out-turned flanges throughout the length thereof, and a tension member consisting of a rolled channel section having a thickened portion extending longitudinally throughout the length of the web thereof, said section being pressed intermediate its ends to fish belly shape, leaving flat end portions and lateral out-turned flanges extending throughout the length of the section, said end portions and flanges being riveted to the flanges at the outer edges of the side walls of said compression member, reinforcing diaphragms located within the ends of said bolster and secured to the top web of the compression member and to the flattened ends of the tension member.

34. A car bolster comprising an integral rolled steel compression member consisting of a top web with outwardly opening channel members extending along either edge thereof and an integral rolled steel tension member of fish belly shape having flattened ends secured to the ends of said channel

members and having flanges intermediate its ends secured to the lower flanges of said channel members, the web of said tension member having a thickened portion extending longitudinally throughout the length thereof, and reinforcing diaphragms located within the ends of said bolster and secured to the top web of the compression member and to the flattened ends of the tension member.

35. A car bolster comprising a compression member consisting of a rolled section of channel form, the web of said section being extended into lateral flanges extending outwardly throughout the length of said section, the outer edges of the side walls having inturned and out-turned flanges throughout the length thereof, and a tension member consisting of a rolled channel section having a thickened portion extending longitudinally throughout the length of the web thereof, said section being pressed intermediate its ends to fish belly shape, leaving flat end portions and lateral out-turned flanges extending throughout the length of the section, said flat end portions being riveted to the inturned flanges at the outer edges of the side walls of the compression member and said lateral flanges being riveted to the out-turned flanges of said side walls of the compression member, reinforcing diaphragms located within the ends of said bolster and secured to the top web of the compression member, and to the flattened ends of the tension member.

36. A compression member for a car bolster consisting of a single rolled section of channel form, the web of which has lateral extensions forming flanges outside of the side-walls of said section, said side walls having wings or flanges at their outer edges, thus forming laterally opening channel sides.

37. A compression member for a car bolster consisting of a single rolled section of channel form, whose web has lateral extensions forming flanges outside of the side walls of said section, said side walls at both sides of their edges opposite the base web having lateral wings or flanges forming with the side walls and base web, and base web lateral extensions, side members of substantially I-beam form.

38. A tension member for a car bolster formed of a single rolled channel section having lateral wings at the edges of its flanges and having a thickened strengthening portion extending longitudinally throughout the length of the web, said section intermediate its ends being pressed to fish belly shape, whereby said strengthening member forms a strengthening chord throughout the fish belly portion of said section.

39. A tension member for a car bolster

consisting of a single rolled channel section having lateral wings at the outer edges of its flanges and having a thickened strengthening portion extending longitudinally throughout the length of the web, said section being pressed to fish belly shape intermediate its ends, leaving flattened ends and laterally extending flanges for securing said section to the compression member of a car bolster, said thickened portion forming a strengthening chord throughout the length of said section including the depressed fish belly portion thereof.

40. A tension member for a car bolster consisting of a single rolled channel section having lateral wings at the outer edges of its flanges and having a thickened strengthening portion extending longitudinally throughout the length of the web, said section being pressed to fish belly shape intermediate its ends, leaving flattened ends and laterally extending flanges for securing said section to the compression member of a car bolster, said thickened portion forming a strengthening chord throughout the length of said section including the depressed fish belly portion thereof, the side edges of said section being trimmed at the ends to bring the section to whatever width is desired.

41. A king pin receiving and bolster reinforcing member consisting of a rolled section of channel form having members adapted to be secured to the inner side of the side walls of a hollow bolster, said channel portion having diaphragms secured therein.

to form a socket for the reception of the lower end of the king pin.

42. A car part, comprising an integral rolled steel compression member, consisting of a top web with outwardly opening channel members extending along either edge thereof, and an integral rolled steel tension member of fish belly shape having flattened ends secured to the ends of said channel members and having flanges intermediate said ends secured to the lower flanges of said channel member.

43. A car part, comprising an integral rolled steel compression member, consisting of a top horizontal web and side walls of channel form and an integral rolled steel tension member of fish belly shape, having flattened ends secured to the lower flanges of said channel members, and having lateral flanges intermediate of its ends also secured to the lower flanges of said channel members.

44. A car part consisting of a single rolled section of channel form, the web of which has lateral extensions forming flanges outside of the side walls of said section, said side walls having wings or flanges at their outer edges, thus forming laterally opening channel sides.

In testimony whereof, I the said SAMUEL A. BENNER have hereunto set my hand.

SAMUEL A. BENNER

Witnesses:

JOHN F. WILL,
J. R. KELLER.
